US0D1077910S

(12) **United States Design Patent** (10) **Patent No.:** **US D1,077,910 S**
(45) **Date of Patent:** **** Jun. 3, 2025**

(54) **MEDALLION**

(71) Applicant: **PepsiCo, Inc.**, Purchase, NY (US)

(72) Inventors: **Martin Eduardo Broen**, New York, NY (US); **Stephen Lim**, Chappaqua, NY (US); **Kai Xiang Lin**, Flushing, NY (US); **Christopher Andrew Gregory**, New York, NY (US); **Stefano Benito Giuliani**, Brooklyn, NY (US); **Carl Gerhards**, New York, NY (US); **Leon David Imas**, Dobbs Ferry, NY (US)

(73) Assignee: **PepsiCo, Inc.**, Purchase, NY (US)

(**) Term: **15 Years**

(21) Appl. No.: **29/887,561**

(22) Filed: **Mar. 22, 2023**

(51) **LOC (15) Cl.** **20-03**

(52) **U.S. Cl.**

USPC **D20/28**; D11/116; D20/42; D20/10

(57) **CLAIM**

The ornamental design for a medallion as shown and described.

DESCRIPTION

FIG. 1 is a top front isometric view of a medallion showing the claimed design;

FIG. 2 is a bottom front isometric view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is a front perspective view thereof showing the claimed design in an environment in which it may be used. The PEPSI logo shown in the drawings is a registered trademark of PepsiCo, Inc.

The broken lines in the figures show environment that forms no part of the claimed design.

1 Claim, 7 Drawing Sheets
